Merchant and Kiegan

UNITED STATES PATENT OFFICE

DAVID FISCHBEIN, OF MINNEAPOLIS, MINNESOTA

FAN ATTACHMENT FOR SEWING MACHINES

Application filed December 14, 1931. Serial No. 580,868.

My present invention has for its object the provision of an extremely simple and highly efficient fan attachment for sewing machines, the purpose of which is to create a current of air to cool the operator of the machine.

To the above end, the invention consists of the novel devices and combinations of devices hereinafter described and defined in the claims.

10 In the accompanying drawing, which illustrates the invention, like characters indicate like parts throughout the several views.

Referring to the drawing:

Fig. 1 is an outer face view of the fan attachment applied to the hand wheel of a sewing machine;

Fig. 2 is a view partly in elevation and partly in section taken on the line 2-2 of Fig. 1, on an enlarged scale; and

20 Fig. 3 is an inner face view of the secondary clamping rim removed from the fan attachment.

For the purpose of showing the invention applied in working position there is fragmentarily illustrated in the drawing a sewing machine and of the parts thereof it is important to note the head 4, the main shaft 5, having a pulley 6 over which runs a belt 7 from any suitable source of power, and a hand or flywheel 8 which is integral with said pulley.

The improved fan attachment comprises an outer rim 9, an inner main clamping rim 10, fan blades 11, which afford oblique braces that connect said two rims, and a secondary segmental clamping rim 12. The outer rim 9 and main clamping rim 10 are continuous and unbroken throughout their entire circumference and said outer rim is concavo-convex in cross-section with the channel in its back. It will be noted that the fan blades 11 are integral with the outer edge of the main clamping rim 10 and the outer end portions of said blades are tightly fitted in the channelled back of the outer rim 9 to connect said outer rim thereto. If the frictional contact between the outer rim 9 and the fan blades 11 is not sufficient to hold said rim for rotation with the fan blades 11 the same may be connected by solder or other-

wise. Both clamping rims 10 and 12 are axially aligned and their opposing faces are channelled to receive the hand wheel 8 therebetween, which is round or substantially round in cross-section, for self-centering engagement therewith.

The main clamping rim 10 is applicable to the outer side of the rim of the hand wheel 8 by an axial movement over the pulley 6 and the segmental secondary clamping rim 12, which is more than a half a circle, is applicable over the boss on the head 4 through which the shaft 5 extends by a radial movement and onto the respective side of the rim of the hand wheel 8 by an axial movement.

A flange 13 is formed with the inner edge of the main clamping rim 10 and a similar flange 14 is formed with the inner edge of the secondary clamping rim 12. The two flanges 13 and 14, which are substantially parallel, are connected, as shown, by three screw bolts 15 which extend through aligned holes in said flanges at circumferentially spaced points substantially equidistant apart. Obviously, by tightening the screw bolts 15 the two flanges 13 and 14 will be drawn toward each other and frictionally clamp the rims 10 and 12 onto the sides of the rim of the hand wheel 8 with a self-centering action due to the concave sides of said rims and the convex sides of the rim of the hand wheel 8. This fastening means rigidly secures the fan attachment to the hand wheel 8 for rotation therewith.

The outer rim 9 and the secondary clamping rim 12 are each formed from a single sheet of metal and the main clamping rim 10 and fan blades 11 are also formed from a single sheet of metal, thus making a construction that is extremely simple and of comparatively small cost to manufacture.

The fan attachment may be very quickly applied to the hand wheel of a sewing machine without removing or changing any of the parts thereof and its outer rim 9 takes the place of the rim of the wheel 8 which, as is well known, is used almost continuously by the operator in slowing up or stopping the machine. The face of the rim 9 is smooth and unbroken so that there is no danger of

injury to the operator's hand which is in contact with said rim. The fan blades 11, two clamping rims 10 and 12, as well as the screw bolts 15 are entirely within the field of the outer rim 9 so that there are no projecting parts on which the operator would be liable to be hurt or injured. The clamping rims 10 and 12 and the screw bolts 15 securely hold the fan attachment on the wheel 8 so that there is no danger of the same loosening up during the rotation of the hand wheel 8.

What I claim is:

15. 1. A fan of the class described, comprising an outer rim, a main clamping rim, a secondary clamping rim, fan blades connecting the outer rim and the main clamping rim, said two clamping rims being axially aligned, the opposing sides of the two clamping rims being channeled to receive the rim of a rotatable wheel therebetween for self-centering engagement therewith, and fastening means connecting the two clamping rims transversely of the wheel and operable to draw the same onto the rim of the wheel.
20. 2. A fan of the class described, comprising an outer rim, a main inner clamping rim, a secondary segmental clamping rim, said two clamping rims being axially aligned, the opposing sides of the clamping rims being channeled to receive the rim of the rotatable wheel therebetween for self-centering engagement therewith, said clamping rims having on their inner edges a pair of flanges that are substantially parallel, and screw-acting means connecting the two flanges transversely of the wheel for drawing the two clamping flanges toward each other and for clamping the same onto the rim of the wheel.
25. 3. The structure defined in claim 2 in which the back of the outer rim is channeled, and in which the fan blades are integral with

the main clamping rim and their outer end portions fitted in the channeled back of the outer rim to secure the outer rim thereto.

4. A fan of the class described, comprising an outer rim, a main clamping rim and a secondary clamping rim, fan blades connecting the outer rim and the main clamping rim, said main clamping rim being applicable to the outer side of the rim of a wheel mounted on the outer end of a shaft by an axial movement of the fan toward said wheel, said secondary clamping rim being transversely divided whereby, the same may be applied around the shaft by a radial movement with respect thereto and applied to the inner side of the rim of the wheel by an axial movement, and means connecting the two clamping rims and operable to clamp the same onto the rim of the wheel.

5. A fan of the class described, comprising an outer rim, an inner rim, and fan blades connecting the two rims, each of said rims being continuous and unbroken, said inner rim being applicable to the outer side of a wheel on the outer end of a shaft by an axial movement toward said wheel, and fastening means for holding the inner rim clamped onto the rim of the wheel, the bodies of the blades being in the same plane as the wheel, two edge portions of each blade extending obliquely on opposite sides of the respective body and in opposite directions to the direction of rotation of the wheel.

6. A fan of the class described comprising an outer rim, an inner rim and blades connecting said rims, said inner rim being channeled to receive the rim of a rotatable wheel for self-centering engagement therewith, and fastening means for drawing the inner rim axially onto the rim of the wheel.
